(57) **CLAIM**

The ornamental design for a container for packaging products, as shown and described.

DESCRIPTION

FIG. 1 is a perspective view of a container for packaging products according to a first embodiment, showing the front, bottom and right side of the first embodiment;

FIG. 2 is a front view of the container for packaging products shown in FIG. 1, wherein a back view is mirror image of the front view;

FIG. 3 is left side view of the container for packaging products shown in FIG. 1, wherein the right side view is a mirror image of the left side view;

FIG. 4 is top down view of the container for packaging products shown in FIG. 1, wherein the bottom up is a mirror image of the top down view;

FIG. 5 is a perspective view of the container for packaging products shown in FIG. 1;

FIG. 6 is a perspective view of a container for packaging products according to a second embodiment, showing the front, bottom and right side of the second embodiment;

FIG. 7 is a front view of the container for packaging products shown in FIG. 6, wherein a back view is mirror image of the front view;

FIG. 8 is left side view of the container for packaging products shown in FIG. 6, wherein the right side view is a mirror image of the left side view;

FIG. 9 is top down view of the container for packaging products shown in FIG. 6, wherein the bottom up is a mirror image of the top down view; and,

FIG. 10 is a perspective view of the container for packaging products shown in FIG. 6.

The broken lines in the drawings illustrate environment and form no part of the claimed design.
